FREDERICK E. GREENE, OF MOUNT VERNON, NEW YORK, ASSIGNOR TO THE MOUNT VERNON COMPANY, SILVERSMITHS, INC., OF MOUNT VERNON, NEW YORK, A CORPORATION OF NEW YORK.

DESIGN FOR A TRIMMING-PLATE FOR AN AUTOMOBILE-DOOR LOCK OR SIMILAR ARTICLE OF MANUFACTURE.

56,142.

Specification for Design. Patented Aug. 24, 1920.

Application filed February 16, 1920. Serial No. 359,005. Term of patent 7 years.

To all whom it may concern:

Be it known that I, FREDERICK E. GREENE, a citizen of the United States, residing at Mount Vernon, Westchester county, State of New York, have invented a new, original, and ornamental Design for a Trimming-Plate for an Automobile-Door Lock or Similar Article of Manufacture, of which the following is a specification, reference being had to the accompanying drawing, forming a part thereof.

In said drawing:

Figure 1 is a front view of a trimming plate embodying my design.

Fig. 2 is an edge view of the same.

I claim—

The ornamental design for a trimming plate for an automobile door lock or similar article of manufacture substantially as shown.

FREDERICK E. GREENE.
